(57) **CLAIM**

The ornamental design for an air-conditioning outlet, as shown and described.

DESCRIPTION

FIG. 1 is a front view of an ornamental design for an air-conditioning outlet showing my new design, a right side view being a mirror view of the left side view.

FIG. 2 is a rear view of the air-conditioning outlet of FIG. 1.

FIG. 3 is a left side view of the air-conditioning outlet of FIG. 1.

FIG. 4 is a top view of the air-conditioning outlet of FIG. 1.

FIG. 5 is a bottom view of the air-conditioning outlet of FIG. 1.

FIG. 6 is a bottom perspective view of the air-conditioning outlet of FIG. 1.

FIG. 7 is a section view of the air-conditioning outlet of FIG. 1, taken along 7-7 in FIG. 4.

FIG. 8 is a section view of the air-conditioning outlet of FIG. 1, taken along 8-8 in FIG. 1.

FIG. 9 is an enlarged view showing a portion of the section view of FIG. 7 as indicated within the dashed-dot lines; and, FIG. 10 is a section view of the air-conditioning outlet of FIG. 1, taken along 10-10 in FIG. 1.

The broken lines in FIGS. 5-10 show a panel of the air-conditioning outlet, and form no part of the claimed design. The dashed-dot lines shown in FIGS. 7 and 9 are to illustrate the enlarged portion of FIG. 7 that is shown in FIG. 9 only, and said dashed-dot lines form no part of the claimed design.
